(57) **CLAIM**

The ornamental design for an articulated equipment support arm, as shown and described herein.

DESCRIPTION

FIG. 1 is a front perspective view of an articulated support arm in a “pin-up” configuration.

FIG. 2 is a left side elevational view thereof.

FIG. 3 is a top plan view thereof.

FIG. 4 is a bottom plan view thereof.

FIG. 5 is a front elevational view thereof.

FIG. 6 is a rear elevational view thereof.

FIG. 7 is a side elevational view in an upward position;

FIG. 8 is a side elevational view in a level position; and,

FIG. 9 is a side elevational view in a downward position. Any broken lines are included solely for the purpose of illustrating the unclaimed portions of the article and form no part of the claims.
